UNITED STATES PATENT OFFICE.

ARTHUR S. BALDWIN, OF BALTIMORE, MARYLAND.

SAFETY-FUSE.

1,239,248.

Specification of Letters Patent. Patented Sept. 4, 1917.

Application filed April 18, 1917. Serial No. 162,263.

To all whom it may concern:

Be it known that I, ARTHUR S. BALDWIN, a citizen of the United States, residing at Baltimore, in the State of Maryland, have invented certain new and useful Improvements in Safety-Fuses, of which the following is a specification.

This invention relates to improvements in safety fuses for shells or projectiles and is an improvement in that class of fuses known in the art as inertia operated fuses in which a firing pin and plunger are normally held in a safety or unarmed position and become shifted to an armed position due to the set back of the parts when the shell containing the fuse is fired from a gun.

The present invention has for its object to improve the structures in the class of fuses referred to; to simplify their construction and reduce the cost of the same.

With these, and other objects in view, the invention is illustrated in the accompanying drawing wherein,—

Figure 1, shows the improved fuse device in longitudinal section,—the parts being in the safety or unarmed position.

Fig. 2, illustrates the device in cross-sectional detail,—the section being taken on the line 2—2 of Fig. 1.

Fig. 3, shows another longitudinal section through the fuse with the plunger and firing pin locked together in a setback or armed position, and

Fig. 4, illustrates a cross-sectional detail of the latter,—the section being taken on the line 4—4 of Fig. 3.

In the drawing, the numeral 5, designates the case or stock of the fuse which is provided with an interior circular cavity or chamber 6, and whose exterior has screw-threads 7, by means of which the stock is attached to the shell. The inner end of the fuse stock is closed, in the present instance by a cap or plug 8, in which is located the primer 9, which latter, when detonated, will fire the main charge in the shell.

A plunger body 10, is carried in the chamber 6, of the fuse stock and said body has central passages 11, and 12, respectively, of

which the passage 12, is of a somewhat lesser diameter than the passage 11, and is at the inner end of the body. These passages communicate with each other so that the plunger body has a central opening extending entirely through it, and at that point where the two passages communicate from an annular shoulder 13.

The plunger body also has an interior annular channel 14, beneath or at the outer side of said shoulder 13, and this annular channel forms a cavity, which in diameter is greater than the diameter of either passage 11, or 12, all for a purpose which will presently be explained.

The firing pin comprises a central longitudinally-extending body whose outer end 15, is of a diameter to freely enter the larger passage 11, of the plunger-body and whose inner end 16, is of a size or diameter to freely enter the smaller passage 12, of said plunger body.

Around the base of the smaller portion 16, the firing pin is provided with an annular cavity 17, so that the diameter of the pin-body at said cavity is less than the diameter of the portions 15 or 16, and this construction produces two slightly spaced shoulders 18 and 19, on the pin body both of which are exposed to the interior of the larger passage 11, of the plunger-body.

The extreme inner end 20, of the pin is held in alignment with the primer and is tapered to effect a detonation of the latter, as will hereinafter be explained.

Normally, the pin-body and the plunger body are held in the stock cavity with the inner end of the plunger body close to the primer and the larger outer end of the pin body seated against the outer end-wall 21, of the stock cavity. The parts are normally held in this position by means of a shear pin 22, which passes diametrically through the smaller portion 16, of the pin-body so that its two ends 23, may project slightly from the pin-body and engage the annular shoulder 13, on the plunger-body. These pin-ends 23, it will be noted, will, in the normal safety position of the parts, have position

at diametrically opposite sides of the annular channel 14, in the plunger body and will just clear the annular wall of the larger plunger-body passage.

- 5 It is therefore to be understood that the plunger-body and pin-body are held at opposite ends respectively of the stock-chamber by means of the ends 23, of the shear pin 22, and this position is termed the safety position because the firing end 20, of the pin is confined in the smaller passage 12, of the plunger body and held against movement toward the primer.

When in the position thus described, the 15 fuse may be handled with safety, and such shocks or jars as it may receive in the course of handling or shipment will be insufficient, to shear the pin-ends. This, therefore is the safety position in which the fuse parts are 20 retained when the fuse is attached to the shell and up to the moment of firing the shell from a gun.

When the shell is fired, the case or stock 25 is driven, suddenly forward with a tremendous shock, while the tendency of the plunger body is to remain inert. This action causes the pin-body to be moved forward with the stock and shear the ends 23, of the pin 22, on the shoulder 13, due to the set- 30 back of the plunger-body, and the pin-body will move forward through the plunger body until the sheared ends 24, shown in Figs. 3 and 4, of the drawing, are compressed between the shoulder 13, of the 35 plunger-body and the shoulder 18, of the pin-body. When these pin-ends 24, are subjected to blows by the two shoulders 13 and 18, from opposite sides, they will have position in register with the annular channel 40 14, on the plunger body and the annular cavity 17, on the pin-body and the effect of the blow on said pin-ends is to flatten and spread said ends until they project into the registered channel and cavity and thereby 45 act as a key to lock the plunger-body and pin-body together as shown in Figs. 3 and 4.

It will thus be understood that upon the shock of firing the fuse in a shell from a gun, the set back of the plunger-body will 50 shear the pin-ends and the latter will be flattened between the shoulders 13 and 18, and spread sufficiently to lock the plunger and pin-body together in the so-called armed position, with the end 20, of the pin 55 projecting from the inner end of the plunger body.

When the armed shell strikes, the locked-together plunger-body and pin-body will both move forward until the end 20, of the 60 pin strikes and detonates the primer and thereby causes an explosion of the shell.

Having described my invention what I claim is,—

1. In a fuse device for shells or projec-

tiles the combination with a case or stock 65 having a chamber therein, of an explosive element; a plunger-body in said chamber which body is provided with a passage with an interior shoulder between its two ends; a firing pin entering the plunger-body passage and extending beyond the shoulder therein; shear means to normally lock the plunger-body and firing pin in a safety position at said interior shoulder, and means on the firing pin to be engaged by the 70 sheared-off portion of the said shear means and lock the body and firing pin in an armed position at said interior shoulder.

2. In a fuse device for shells or projectiles the combination with a case or stock 80 having a chamber therein, of an explosive element; a plunger-body in said chamber said body having communicating central passages of unequal diameters whereby to 85 form a shoulder; a firing pin-body in said plunger passages and said pin-body having a shoulder thereon, and shear means projecting in the larger of said plunger passages to normally hold the two bodies in a safety position and the sheared part of 90 which will engage the shoulder on the pin-body to lock the bodies in an armed position upon the shock of firing.

3. In a fuse device for shells or projectiles the combination with a case or stock 95 having a chamber therein, of an explosive element; a plunger-body in said chamber,— said plunger-body having communicating central passages of unequal diameters whereby to form a shoulder; a firing pin- 100 body having smaller and larger portions to enter said plunger-body passages and also having a shoulder thereon, and a shear pin having its ends normally extending cross-wise of the larger of the plunger-body passages and engaging the shoulder of the plunger body and said shear pin-ends being compressible at the shoulders on the two bodies on the set-back of the plunger to lock 105 the two bodies together in an armed position.

4. In a fuse device for shells or projectiles the combination with a case or stock having a chamber therein, of an explosive element; a plunger-body in said chamber; 115 a firing pin body extending into the plunger-body and provided with an annular cavity, and a shear pin carried by the pin-body and having an end engaging the plunger-body said pin-end when sheared serving 120 to enter the cavity in the pin to lock the two bodies together.

5. In a fuse device for shells or projectiles the combination with a case or stock 125 having a chamber therein, of an explosive element; a plunger-body in said chamber and having central passages of unequal diameters whereby to form a shoulder,—said

body also having an annular channel at said shoulder; a firing pin-body extending into the plunger-body and provided with an annular cavity, and a shear pin extending through the firing pin-body and having its ends projecting beneath the shoulder of the plunger-body and said shear-pin ends when sheared serving to enter the channel and

cavity of the two bodies to lock the same in an armed position.
